UNITED STATES PATENT OFFICE

FREDERICK W. C. NEUNER, OF CONNERSVILLE, INDIANA, ASSIGNOR TO INDIANA
LAMP CORPORATION, OF CONNERSVILLE, INDIANA, A CORPORATION

DESIGN FOR A HEAD LAMP

Application filed January 24, 1930. Serial No. 34,265. Term of patent 7 years.

To all whom it may concern:

Be it known that I, FREDERICK W. C. NEUNER, a citizen of the United States, residing at Connorsville, in the county of Fayette and State of Indiana, have invented a new, original, and ornamental Design for Head Lamp, of which the following is a specification, reference being had to the accompanying drawing, forming part thereof.

In the drawing, the figure is a perspective view of a head lamp, showing my new design, the ornamental effect being duplicated upon opposite sides but not upon the front and rear.

I claim:

The ornamental design for a head lamp, substantially as shown and described.

FREDERICK W. C. NEUNER.
